UNITED STATES PATENT OFFICE

161,058

AIR CIRCULATOR

Ford Se Bastian, Chicago, Ill., assignor to Chicago
Electric Manufacturing Company, Chicago, Ill.,
a corporation of Illinois

Application December 10, 1949, Serial No. 6,557

Term of patent 3½ years

(Cl. D62—4)

To all whom it may concern:

Be it known that I, Ford Se Bastian, a citizen of the United States, residing in Chicago, Cook County, State of Illinois, have invented a new, original, and ornamental Design for an Air Circulator, of which the following is a specification, reference being had to the accompanying drawing, forming a part thereof;

Fig. 1 is a front elevational view of an air circulator, showing my new design;

Fig. 2 is a top plan view thereof;

Fig. 3 is an end elevational view thereof.

The dominant features of my design reside in the portions illustrated in solid lines.

I claim:

The ornamental design for an air circulator, as shown and described.

FORD SE BASTIAN.
